UNITED STATES PATENT OFFICE

JOHN G. STANWAY, OF WHEELING, WEST VIRGINIA, ASSIGNOR TO THE SALEM POTTERY CO., DOING BUSINESS AS THE SALEM CHINA COMPANY, OF SALEM, OHIO

DESIGN FOR A PLATE

Application filed April 15, 1932. Serial No. 43,508. Term of patent 3½ years.

To all whom it may concern:

Be it known that I, JOHN G. STANWAY, a citizen of the United States, residing at Wheeling, in the county of Ohio and State of West Virginia, have invented a new, original, and ornamental Design for Plates, of which the following is a specification, reference being had to the accompanying drawing, forming part thereof.

Figure 1 is a plan view of a plate, showing my new design; and

Fig. 2 is a detail view of the die pattern used in decorating the plate.

I claim:

The ornamental design for a plate, as shown.

JOHN G. STANWAY.
